CLAIM

The ornamental design for a converter for sanitary outlet valves, as shown and described.

DESCRIPTION

FIG. 1 is a top plan view of a converter for sanitary outlet valves in accordance with my design;

FIG. 2 is a top, front, right perspective view thereof;

FIG. 3 is a bottom plan view thereof;

FIG. 4 is a bottom, rear, left perspective view thereof;

FIG. 5 is a front elevational view thereof;

FIG. 6 is a right side elevational view thereof;

FIG. 7 is a rear elevational view thereof; and,

FIG. 8 is a left side elevational view thereof.

1 Claim, 8 Drawing Sheets
